UNITED STATES PATENT OFFICE

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE

MEASURING-TAPE REEL

Application filed June 22, 1928. Serial No. 237,403.

This invention relates generally to measuring tapes and particularly to the construction of the cases thereof, and has for its object the simplicity of construction and cheapening of the cost of manufacture thereof.

The present invention comprises a continuation in part of that shown in my co-pending application for U. S. Letters Patent, Serial No. 221,442, filed November 7, 1927.

10 One of the objects of my invention is to provide a simple form of measuring case that may be quickly assembled and yet have all of the strength and durability of the more complicated prior constructions.

15 Another object of my invention is the provision of an outer or finishing cover for the measuring tape case that may be quickly placed on the case and there be held without the use of stitching or other similar means 20 or without the unprotected edges of the covering being exposed.

25 Still another object of my invention resides in the formation of a measuring tape case wherein the sectional parts of the case are covered with flexible material such as cloth or leather, and wherein the free edges of the covering material are disposed at a counter-sunk peripheral rim of the case, and wherein these edges are cemented in such a 30 position to the walls of the case and are covered by a finishing band of metal, or other flexible material which loosely overlies the free edges so as to hide them and to provide a finish for the rim of the case and wherein 35 the finishing band is held in position by the shoulders of the peripheral counter-sunk portion.

These and other objects of my invention will be apparent from a perusal of the following specification when taken in connection with the accompanying drawings wherein:

40 Figure 1 is a front view of my improved tape reel with certain parts broken away;

45 Figure 2 is a sectional view therethrough;

Figure 3 is an enlarged fragmentary sectional view; and

Figure 4 is a similar view of another arrangement.

50 Heretofore it has been customary to tele-

scope the two parts of a measuring tape case over the drum and other parts of the device and hold these parts in such positions by means of additional or other elements. The present invention contemplates providing 55 the overlapping or telescoped portions of the case with beads, which when the parts of the case are telescoped snap into self-holding interlocking engagement. Thus the case is assembled and held by a means forming a part 60 of the case itself and the necessity of other elements functioning for this purpose is done away with.

Where the case has been provided with an 65 outer cover of leather or other material it has been the practice to form such outer cover in two sections and to stitch the adjoining edges of these sections one to the other. This has been unsatisfactory because of its expense 70 as a manufacturing operation and the fact that it does not present a finished or attractive appearance. This invention, while utilizing a cover made in two sections, does not require the stitching thereof. It provides a 75 cover which is placed on the case as a part of the assembling thereof, but which is so held in place that there are no exposed edges to become loosened, and a pleasing and finished appearance is presented. This is accomplished by means of a finishing strip 80 secured over the adjoining edges of the cover and held at its ends by the eyelet or frame carrying the roller over which the tape line passes when removed from the case.

Reference being had more particularly 85 to the drawings, 10 and 12 designate two telescoping parts of a measuring tape case. The portion of these parts that are designated to telescope are provided at or adjoining their edges with inward beads or grooves 14 and 16. When the parts 10 and 12 of the case are telescoped, these beads 14 and 16 snap into interlocking self-holding engagement and retain the casing assembled. Each section 10 and 12 is provided with an outwardly projecting rounded hollow bead-like portion 18 and 20 and the free edge of each section is somewhat countersunk or depressed peripherally as at 22 and 24 so as to provide, when the sections are telescoped and interlocked, 100

as shown in Figure 3, a peripheral counter-sunk portion of the rim of the case. These metal sections 10 and 12 are adapted to ornately be covered by flexible coverings 26 and 28 which may be of leather, canvas, or any flexible material. The free edges 30 and 32 of these coverings 26 and 28 are adapted to lie in the peripheral counter-sunk portion and these coverings are cemented to the cases of metal or other material by means of a suitable cement so that in the form of the invention shown in Figure 3, the free edges 30 and 32 will lie in juxtaposed position as shown thereat, while the form shown in Figure 4 may be arranged to overlie one another in the peripheral groove. The cement is the sole means for fastening the cover pieces 26 and 28 to the casing sections. However, I provide means for hiding these overlapping or juxtaposed edges of the cover pieces and to this end, I provide an ornate band or ribbon of metal, leather, or other suitable material 36, which is adapted loosely to overlie the free edges 30 and 32 of the cover pieces 26 and 28. The free ends of this metal strip 36 are adequately anchored in position in the frame or eyelet 15, the ends of the metal pieces being bent around the edges of the window or opening as shown in the drawings and held in firm position by the eyelet or frame thereat. One of the important features of my invention resides in having the hiding band or finishing band 36 held in the counter-sink of the casing and directly overlying the cemented edges of the cover pieces 26 and 28 so as to provide a very neat finish for the casing and the two peripheral beads 18 and 20 of the casing sections provide adequate shoulders for preventing lateral or side play of the finishing band 36 and prevent it from being dislodged. In other words, these shoulders 18 and 20 centralize the band and hold it in position, hiding the raw edges of the cover pieces, and at the same time give the casing the ornate finish and appearance desired. The construction of the central part of the tape and the hub is substantially that shown in my pending application, Serial No. 130,219, filed August 19, 1926, and therefore no claim is made to the latter features, the same being covered in my prior application.

Having thus described my invention, what I claim as new and desire to secure by Letters Patent is:

1. In a tape reel, a multi-part casing having flanged portions in interfitting engagement, outstanding shoulders formed in said flanged portions to define a peripheral groove, cover pieces for said casing having portions terminating in said groove, and a finishing band overlying the edges of said cover and hiding the same, said band being confined against lateral movement by said peripheral shoulders.

2. A tape reel, comprising multi-part sec-

tions having flanged portions in interfitting engagement and formed to provide a peripheral groove defined by outstanding shoulders formed in the flanged portions, cover pieces for said casing, said cover pieces being cemented to said casing, and a metal band loosely overlying said pieces at the periphery of the casing so as to hide the same, said band having its free ends held in position by the eyelet of said casing and confined against lateral displacement by the shoulder.

3. A tape reel casing formed of sheet metal and having a peripheral groove, defined by opposed outstanding shoulders, formed in its edge, cover pieces for the sides of the casing having terminal portions extending in said groove and secured to the casing and a finishing band overlying the terminal portions of said cover pieces in the groove to hide the same, said band being confined against lateral movement between said opposed shoulders.

4. In a tape reel, a multi-part casing having interengaging portions providing a peripheral groove in its edge, cover pieces for said casing having marginal portions arranged in said groove and cemented firmly to the casing and a finishing band loosely overlying the free edges of said cover pieces and hiding the same, said finishing band lying in the peripheral groove.

5. In a tape reel, the combination of a multi-part casing joined together at the periphery of the casing and formed to provide a peripheral groove, cover pieces for said casing, said cover pieces terminating in the groove and cemented to the casing and a finishing band loosely overlying the free edges of the cover pieces, said finishing band being anchored in position by having its free ends attached to the casing.

6. In a tape reel, a casing having a peripheral groove defined by spaced shoulders formed in the casing, cover pieces for the casing having their marginal portions disposed in the groove and secured to the casing and a finishing band overlying the edges of the cover pieces to hide the same and extending in the groove between the shoulders and retained in place thereby.

7. In a tape reel, a sheet metal casing having a peripheral groove defined by spaced apart peripheral shoulders formed in the casing, cover pieces for the casing having their marginal edges arranged in the groove and a finishing band comprising a strip secured at its opposed ends to the casing, overlying the edges of the cover pieces to hide the same in the groove, said band lying in the groove between the shoulders and retained in place thereby.

8. In a tape reel, a sheet metal casing having a peripheral groove defined by spaced apart peripheral shoulders formed in the casing, cover pieces for the casing having their marginal edges arranged in the groove said

casing having an opening in its periphery and an eyelet arranged in the opening and a finishing band comprising a strip secured at its opposed ends to said eyelet, overlying the edges of the cover pieces to hide the same in the groove, said band extending in the zone between the shoulders and retained in place thereby.

9. In a tape reel, a sheet metal casing having a peripheral groove defined by spaced apart peripheral shoulders formed in the casing, cover pieces for the casing having their marginal edges arranged in the groove, said casing having an opening in its periphery and an eyelet arranged in the opening and a finishing band comprising a metallic strip secured at its opposed ends to said eyelet and loosely overlying the edges of the cover pieces to hide the same in the groove, said band lying in the groove between the shoulders and retained in place thereby.

10. In a tape case, a casing having side walls and a peripheral wall, cover pieces for the side walls having their marginal portions overlying the peripheral wall of the casing, said marginal portions being arranged in overlapping relation and secured together.

11. In a tape case, a casing having a peripheral recess, cover pieces for the sides of the casing with their marginal portions overlying each other in the peripheral recess.

12. In a tape case, a casing having a peripheral recess, cover pieces for the sides of the casing with their marginal portions overlying each other opposite the peripheral recess, and means for securing the overlying portions in place.

13. A tape case, formed of two sections having inter-connected flanges and formed with a peripheral recess, cover pieces for the casing having overlapping marginal portions arranged to lie in the recess and secured in place therein.

14. A tape case comprising two casing sections having peripheral projecting shoulders and laterally extending connecting portions arranged substantially within the outermost portions of the shoulders to provide a peripheral groove whereby to facilitate the holding of the casing in the hand of an operator.

In witness whereof, I have hereunto subscribed my name.

ADOLPH LANGSNER.
